US00D718984S

(12) **United States Design Patent**
Musumeci

(10) **Patent No.:** **US D718,984 S**
(45) **Date of Patent:** **** Dec. 9, 2014**

(54) **AIR SPOON FOR CHILDREN**

(71) Applicant: **Marco Musumeci**, Saragossa (ES)

(72) Inventor: **Marco Musumeci**, Saragossa (ES)

(**) Term: **14 Years**

(21) Appl. No.: **29/457,435**

(22) Filed: **Jun. 10, 2013**

(30) **Foreign Application Priority Data**

Mar. 25, 2013 (ES) 001365589-0001
